(57) **CLAIM**

The ornamental design for a display screen with graphical user interface, as shown and described.

DESCRIPTION

FIG. 1 is a front view of a first embodiment of a display screen with graphical user interface embodying the new design; and,

FIG. 2 is a front view of a second embodiment of a display screen with graphical user interface embodying the new design.

The outermost broken lines depict the display screen with graphical user interface in which the design is embodied that form no part of the claimed design. The remaining broken lines illustrate portions of the graphical user interface that form no part of the claimed design.

In the first and second embodiments, stippled portions of the image indicate a contrast in appearance. The stippled portions of the image indicate a contrast in appearance. Relatively denser stippled portions indicate a greater contrast in appearance to indicate a gradient.
